DESIGN FOR A COMBINED INKSTAND AND PENCIL RACK

Michael Gren, Rome, N. Y.

Application September 12, 1945, Serial No. 122,051

Term of patent 7 years

(Cl. D74—1)

To all whom it may concern:

Be it known that I, Michael Gren, a citizen of the United States and resident of the city of Rome, county of Oneida, and State of New York, have invented a new, original, and ornamental Design for a Combined Inkstand and Pencil Rack, of which the following is a specification, reference being had to the accompanying drawing, forming part thereof.

Fig. 1 is a top plan view of a combined inkstand and pencil rack showing my new design.

Fig. 2 is a side elevation of said combined inkstand and pencil rack.

Fig. 3 is a front elevation of said combined inkstand and pencil rack.

I claim:

The ornamental design for a combined inkstand and pencil rack, as shown.

MICHAEL GREN.
